(57) **CLAIM**

The ornamental design for a desk lamp with automobile spoiler motif, as shown and described.

DESCRIPTION

FIG. 1 is a perspective view of a desk lamp with automobile

spoiler motif according to the invention in which the base is in the form of an instrument panel and the lamp shade has the form of a spoiler used on an automobile;

FIG. 2 is a front elevational view of the lamp of FIG. 1;

FIG. 3 is a rear elevational view of the lamp of FIGS. 1 and 2;

FIG. 4 is a top plan view of the lamp of FIGS. 1-3;

FIG. 5 is a right side view of the lamp of FIGS. 1-4, the left side view being a mirror image thereof;

FIG. 6 is a cross sectional view taken along line 6—6 of FIG. 2 showing the exact contours or configurations of the lamp shade members not clearly visible in FIGS. 1-5;

FIG. 7 is a front elevational view of an alternative embodiment of the new desk lamp with automobile spoiler motif design;

FIG. 8 is a rear elevational view of the lamp of FIG. 7;

FIG. 9 is a top plan view of the lamp of FIGS. 7 and 8;

FIG. 10 is a right side view of the lamp of FIGS. 7-9, the left side view being a mirror image thereof;

FIG. 11 is a front elevational view of another alternative embodiment of the new lamp design;

FIG. 12 is a rear elevational view of the lamp of FIG. 11;

FIG. 13 is a top plan view of the lamp of FIGS. 11 and 12; and,

FIG. 14 is a right side elevational view of the lamp of FIGS. 11-13, the left side elevational view being a mirror image thereof.

Details shown in dashed dotted lines are for illustrative purposes only and form no part of the claimed design.
